UNITED STATES PATENT OFFICE.

MAX VON RECKLINGHAUSEN, ANDRÉ HELBRONNER, AND VICTOR HENRI, OF PARIS,
FRANCE, ASSIGNEES, BY MESNE ASSIGNMENTS, TO THE R. U. V. COMPANY, INC., A
CORPORATION OF NEW YORK.

STERILIZING LIQUIDS.

1,271,246.

Specification of Letters Patent.

Patented July 2, 1918.

Original application filed December 21, 1912, Serial No. 738,069. Divided and this application filed July 15, 1915. Serial No. 40,036.

To all whom it may concern:

Be it known that we, MAX VON RECKLINGHAUSEN, a subject of the Emperor of Germany, ANDRÉ HELBRONNER, a citizen of the Republic of France, and VICTOR HENRI, a citizen of the Republic of France, all residing at 73 Boulevard Haussmann, Paris, France, have invented new and useful Improvements in Sterilizing Liquids, of which the following is a specification.

This invention relates to vapor electric apparatus and particularly although not exclusively to apparatus of this character which is adapted for the production of ultra-violet rays for the sterilization of liquids and like purposes, is a division of our application Serial No. 738,069, filed December 21, 1912, and has for its object to provide an improved form of vapor electric lamp having a higher efficiency as regards the production of a relatively large amount of ultra-violet rays than has hitherto been possible.

It will be understood that the construction illustrated is at present considered as embodying the best form of the invention which is not limited by the precise details herein described.

In the accompanying drawings, Figure 1 is a plan view of a simple form of mercury vapor lamp of the kind above described, Fig. 2 being a sectional view in side elevation of the lamp shown in Fig. 1.

Figs. 3 and 4 are views in elevation and cross section respectively illustrating a preferred arrangement of cooling device for use when the lamp is employed for sterilizing purposes.

Fig. 5 is a plan view illustrating a modification in the arrangement of the terminals of the lamp shown in the preceding figures, Figs. 6 and 7 illustrating further modifications in detail.

Fig. 8 is a sectional view showing the lamp in position in a simple form of sterilizing apparatus.

In a mercury vapor lamp the container of which is of a given length and diameter and consumes a given constant amount of electrical energy, there exists a definite relation between the quantity of luminous radiation and the quantity of ultra-violet rays emitted by the lamp. If, however, the form of the container be altered so that instead of being

cylindrical with a rectilinear axis the lamp tube is curved into the form of a U so as to 55 constitute two arms closely adjacent to one another, it is found that the electrical conditions being unchanged the quantity of ultra-violet radiation emitted becomes considerably greater. This phenomenon is probably 60 due to the fact that the two arms of the lamp tube re-act upon one another so as to cause a large quantity of heat to be exchanged between the two by radiation.

The U shaped form of container above 65 referred to is obviously not the only form which may be employed in order to produce this increased amount of ultra-violet rays, but in all cases the several portions of the lamp tube must be located sufficiently near 70 together so that an exchange of heat between these portions may occur to a sufficient extent to produce the desired increase in the amount of ultra-violet rays emitted.

A further improvement consists in impressing on the terminals of the lamp a minimum voltage of from 400 to 500 volts, as it has been observed that the increase in the emission of ultra-violet rays due to an increase in the impressed voltage is not proportional to the increase in the latter, but the amount of ultra-violet rays emitted increases much more rapidly than the increase in the voltage impressed on the terminals of the lamp. As an example it may be mentioned that a lamp constructed and operating in accordance with the two conditions above stated, namely, the arrangement of the lamp tube in the form of a U and by impressing a high voltage upon the terminals thereof when operated at a voltage of approximately 400 volts with a current of three amperes, is found to have a bactericidal activity eleven times greater than a mercury vapor lamp having a straight container operated at 150 80 volts and three amperes, the voltage per centimeter length of the lamp tube being the same in each case.

A lamp of this kind is found to be particularly suitable for use in sterilizing apparatus since the two electrodes of the lamp being located adjacent to one another enable the sterilizing apparatus to be constructed and arranged in a very simple and efficient manner, and various forms of construction 85 of a lamp of this kind for the sterilization

of fluids are illustrated by way of example in the figures of the drawings.

Referring now to Figs. 1 to 5, the mercury vapor lamp 1 is illustrated as comprising a quartz tube of U shape, the two arms of which, 2-3, are located closely adjacent to one another and very nearly in contact. The internal form of the lamp 1 is such as to provide a restricted portion 4 adjacent to the negative electrode, while the lamp tube is flattened as indicated at 5 adjacent to the positive electrode. Between the portions 4 and 5 of the lamp tube and the terminals, piston members 6, 7, are provided between 10 which are located fragments of broken glass 8, the conductors for supplying current to the lamp entering through openings 9 into tubular extensions 10 connected to the lower portions of the arms 2 and 3 in which are 15 located the mercury electrodes.

In this as in other forms of mercury vapor lamps, it is necessary that the electrodes should be cooled to a certain extent, this cooling being usually effected by lateral 20 tubular extensions of chambers to which the lighting tube of the lamp is connected. In the improved lamp as illustrated in the drawings, however, the electrodes are surrounded by sheets of thin aluminium, as indicated at 11, wings or vanes 12 surrounding the sheets 11 being provided so arranged as to be as intimately in contact with the surface of the electrodes as possible. The wings or vanes 12 are preferably of conical 25 form so as to facilitate the introduction of the lamp and particularly the entire luminous tube thereof into the interior of the quartz tubes or chambers of the sterilizing apparatus. A copper clamp indicated at 13 30 is provided which either surrounds each electrode separately or, as shown in Fig. 4, surrounds both of the electrodes and serves to maintain the aluminium sheets 11 in position and to secure the wings or vanes 12 35 thereto.

The portions of the lamp tube containing the electrodes need not necessarily be arranged parallel to one another, but may, as shown in Fig. 1, be arranged at right angles 40 to the lighting tube or at any other suitable angle, as shown in Fig. 5. It is preferable, however, that the angle formed by the portion of the lighting tube containing the electrode relative to the lighting tube itself, 45 should be greater than a right angle in order to permit the lighting tube to be inserted into the sterilizing apparatus, so as to utilize to the full extent the rays emitted from the lamp.

50 The cooling of the electrodes can be obtained by other means than the wings or vanes illustrated; for example, the electrodes can be arranged to be cooled by directing a portion of the liquid in the interior 55 of the sterilizer upon any suitable portion

of the electrodes, or, if it is desired to avoid the formation of rust, a circulation of distilled water or other suitable liquid may be provided for cooling the electrodes and which is itself cooled by air or in any other 70 similar and suitable manner.

The starting into operation of a lamp having a U shaped tube of considerable length requires a somewhat complicated operation, which consists of the following stages:— 75

1. Removing the lamp from the sterilizing apparatus.

2. Tilting the lamp upward about an axis at right angles to the lighting tube.

This latter movement serves to start the 80 lamp into operation but leaves too large a quantity of mercury on the negative electrode side of the lamp. It is therefore necessary to tilt the lamp again about an axis parallel to that of the luminous tube and at 85 the same time about an axis at right-angles to that of the lighting tube, in order to transfer the excess of mercury from the negative electrode to the positive electrode. It is found, however, in practice that with 90 U shaped lamps operating at low voltage which can be started into operation without the movement of any considerable amount of mercury, that starting can be effected by tilting about a single axis, that is to say, 95 an axis parallel to that of the lighting tube, the tube being tilted until one arm is slightly above the other, so that the mercury forms a continuous stream between the two electrodes, whereupon the lamp is returned to 100 its normal position. It is found that the operating life of these lamps can be considerably increased by providing arrangements intended to determine to some extent the path of the luminous arc, devices of this 105 kind being illustrated in Figs. 6 and 7. It has been observed that the luminous arc naturally tends to take the shortest path from one electrode to the other and it necessarily follows that with a lighting tube of 110 U shape the luminous arc instead of tending to traverse the middle of the tube as in the case of a straight lighting tube, tends to approach that side of the curved portion of the lighting tube which is adjacent to the 115 center of curvature, following in fact the line indicated at 14 in Fig. 6. The inner face of the lighting tube is thus exposed by reason of the extremely high temperature of the luminous arc, to much more rapid deterioration than the other portions of the tube and the corrosion thus effected is found after the expiration of a certain time, to cause the wall of the lighting tube at this 120 point to become somewhat porous and permit the entrance of air, thus rendering the lamp inoperative due to the vacuum being impaired. This disadvantage is obviated by the arrangement shown in Fig. 6 in which the deterioration of this portion of the light- 125 130

ing tube and the injurious effect due to such deterioration is prevented by making that portion 15 of the lighting tube of considerably increased thickness, as shown in the 5 figure. The quartz wall being thickened at this point can readily resist without injury the action of the high temperature of the luminous arc.

A modified arrangement for the same purpose is illustrated in Fig. 7 in which in order to maintain the luminous arc away from the wall 15 of the lighting tube any suitable number of projections 16 are provided; the dotted line indicated at 14 illustrates how 10 the luminous arc is kept at a certain distance away from the wall of the lighting tube.

The arrangements illustrated in Figs. 6 and 7 are evidently only examples of particular methods of causing the luminous arc to 20 be maintained in proper position at the curved portion of the lighting tube and prevent its too close approach to the inner wall thereof, and other methods of accomplishing the same result may evidently be adopted 25 without exceeding the scope of the invention.

Fig. 8 illustrates the application of the lamps of the form above described to a simple type of sterilizing apparatus. The latter comprises a casing 17, the interior 30 which is provided with baffle plates 18, a tubular chamber 19 of quartz or other suitable material being arranged at the center of the chamber within which a mercury vapor lamp 1, constructed as above described, 35 is located. The baffle plates 18 are disposed in such a manner that no portion of the apparatus is shaded thereby from the action of the rays emitted by the lamp, these baffle plates serving to secure an energetic agitation 40 of the liquid, which is necessary for effective sterilization. Since no portion of the apparatus is shaded by the baffle plates it is impossible for colonies of bacteria to become established in any portion of the apparatus 45 so as to reinfect the water or other liquid during the sterilizing process.

In the form of sterilizing apparatus illus-

trated the liquid to be sterilized is arranged to be introduced into the apparatus through a pipe 20 arranged tangentially, the outlet 50 pipe 21 being arranged either at the axis of the sterilizing apparatus or on one side thereof.

It will be understood that the improved lamp may be operated either from a direct 55 or an A. C. circuit, as may be most convenient to suit particular conditions, arrangements of any suitable type for starting and maintaining the lamp in operation being provided.

We claim as our invention:

1. The combination in a mercury vapor device of means for causing an interchange of heat between the electrodes of said device and means for preventing injury to the wall 65 of the container due to the passage of the electric discharge through said device.

2. The combination in a mercury vapor device having its electrodes arranged adjacent to each other, of means for deflecting 70 the passage of the electric discharge away from the wall through said device comprising an inwardly extending projection formed upon the wall of said device.

3. The combination in a mercury vapor 75 device of means for effecting an interchange of heat between the electrodes of said device and means for causing a difference of temperature in certain portions of the wall of the device as compared to the remainder. 80

4. The combination in a vapor electric lamp, having a curved container therefor of means for reinforcing a portion of the wall of the container.

In testimony whereof we affixed our signatures in presence of witnesses.
